UNITED STATES PATENT OFFICE.

WILLIAM ILE, OF JACKSON, MICHIGAN, ASSIGNOR TO REYNOLDS SPRING COMPANY,
OF JACKSON, MICHIGAN, A CORPORATION OF DELAWARE.

TWO-WAY SOCKET.

Application filed May 9, 1925. Serial No. 29,147.

The invention relates to a two way socket. The object of the present invention is to improve the construction of two way sockets and to provide a simple, practical and inexpensive two way socket of strong and durable construction having an insulating body molded of a single piece and equipped with longitudinally aligned screw shell contacts and provided with spaced projecting contact fingers arranged at right angles to the longitudinally aligned screw shell contacts and adapted to engage either a fixture to connect the two way socket with the same and also to engage a screw plug for enabling the two way socket to be connected with a fixture or other socket having a screw shell contact.

A further object of the invention is to provide a two way socket of this character adapted to form a two in one structure for presenting either the spaced contact fingers or a screw plug for connection with a fixture or the like.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation of a two way socket partly in section constructed in accordance with this invention and having a screw plug applied to it.

Fig. 2 is a longitudinal sectional view of the two way socket, the screw plug being removed.

Fig. 3 is an end view of the same.

In the accompanying drawing in which is illustrated the preferred embodiment of the invention, a two way socket comprises in its construction a cylindrical insulating body 1 molded of a single piece of phenol condensation product or other suitable material and provided at the top with an exterior cylindrical extension 2 and having a central transverse partition 3 constituting a dividing wall and forming two separate chambers or compartments. The cylindrical

extension is arranged at right angles to the cylindrical body and the central transverse partition wall is located directly below the center of the cylindrical enlargement and extends diametrically thereof and constitutes a brace or support which will enable the two way socket to be plugged in and removed from a fixture without undue strain upon the cylindrical insulating body. The ends of the cylindrical body are flared at 4 and are preferably provided with an exterior annular bead or enlargement 5. The cylindrical extension 2 has embedded in its center an interiorly threaded metallic bushing 6 provided at the inner end with a circumferential projecting annular flange 7 constituting a head and adapted to enable the bushing to be securely anchored within the extension 2 and the said flange 7 may be either smooth or corrugated as desired.

The cylindrical body is provided at opposite sides of the extension 2 with conductor bars 8 and 9 having exteriorly projecting portions forming contact fingers and preferably provided with perforations 10 to engage with suitable protuberances of springs for providing an interlocking contact between the fingers of the conductor bars 8 and 9 and the coating contacts of a screw plug 11 or fixture, or the like with which the two way socket is connected. The conductor bar extends to the center of the dividing partition wall 3 and is equipped at its inner end with a hollow rivet 12 arranged at right angles to the inner portion of the conductor bar 8 and extending longitudinally of the cylindrical body and projecting from the opposite faces of the dividing wall 3. The said conductor bar 8 consists of inner and outer portions connected intermediate of the ends of the conductor bar 8 by a connecting portion 13 arranged at right angles to the said inner and outer portions and formed integral with the same, the conductor bar 8 being constructed of a single piece of metal which is bent at right angles at spaced points and is clearly illustrated in Fig. 2 of the drawing. The transverse or intermediate connecting portion 13 is embedded in the cylindrical extension 2 and the inner portion 14 extends along one of the faces of the wall 3 in flush relation with the same to a point beyond the center thereof, the hollow rivet 12 being located at the center and extending through insulating

disks 15 of grey fiber or other suitable material and piercing and secured to center contacts 16. The center contacts which consists of strips of suitable metal bent to form 5 inner and outer portions are pierced at their inner portions by the said rivet which is headed by a suitable or blades tool, the outer portions being bent back for this purpose. The outer portions are provided with cup 10 shaped portions of protuberances 17 to contact with lamps and they are adapted to be readily bent and arranged in a proper position to provide a proper contact with the lamps.

15 Prior to assembling the insulating disks a pair of screw shell contacts 18 is arranged within the cylindrical body at opposite sides of the partition wall and with their flanges 19 in contact with the same. The partition 20 wall is provided at the lower portion with an opening to permit a rivet 20 to be passed through the partition and secured to the flanges of the screw shell contacts prior to assembling the insulating disks and the center contacts. An inner insulating disk 21 is also arranged between the inner portion 14 of the conductor bar 8 and the flange 19 of the adjacent screw shell contact.

The conductor bar 9 which is L-shaped is 25 also embedded in the cylindrical extension 2 during the operation of molding the insulating body and it consists of a straight body portion and an inner arm 22 which is arranged at the inner face of the cylindrical 30 body at one side of the partition so as to contact with one of the screw shell contacts. An electrical connection is thereby established between the inner arm 22 and one of the screw shell contacts which is electrically 35 connected with the other screw shell contact by the rivet 20 which secures the flanges of the shell contacts to the dividing wall 3.

The conductor bars are located at opposite sides of a central threaded bushing and the latter is adapted to be engaged by the inner threaded end 23 of a screw 24 for securing the plug 11 detachably to the two way socket. When the plug 11 is detachably secured to the two way socket as illustrated 45 in Fig. 1 of the drawing, a two in one device is provided as the device with the parts assembled in this manner is adapted to be screwed into an ordinary screw socket. When, however, it is desired to attach the 50 two way socket to a fixture or other socket having apertures and interiorly arranged contacts, the screw plug is detached by removing the bolt or screw 24. This exposes the projecting portions of contact fingers of 55 the conductor bars 8 and 9 and affords the means for effecting the desired electrical and mechanical connection. The inner end of 60 the screw plug is provided with a flange 25 which fits over and caps the cylindrical extension 2 and the engagement of the contact 65

fingers with the screw plug will prevent any rotary movement of the same on the bolt or screw. It is therefore, necessary to rotate the bolt or screw by a wrench or other tool when it is desired to separate the parts and the 70 said bolt or screw is provided at its outer end with a polygonal head for this purpose.

What is claimed is:

1. A two way socket comprising a cylindrical body of a single piece of molded insulating material provided with an exterior enlargement and having a transverse partition wall located adjacent and bracing the enlargement and dividing the body into two separate compartments, conductor bars 80 embedded in the enlargement, one of the conductor bars terminating at one of the compartments at the inner face of the body and the other conductor bar consisting of offset inner and outer portions and a connecting intermediate portion wholly embedded in the said enlargement, the inner portion of such conductor bar extending to the central portion of the partition wall in flush relation with one of the faces thereof, an insulating disk arranged at the said inner portion of the conductor bar, shell contacts arranged within the said compartment and having flanges electrically connected and secured to the partition wall, one 90 of the shell contacts having electrical connection with the conductor bar which terminates at the inner face of the said body, central contacts secured to the said wall and electrically connected with the said inner 95 portion of the contact bar and insulating disks interposed between the central contacts and the flanges of the shell contacts.

2. A two way socket comprising a cylindrical one piece body having an exterior enlargement at one side between the ends of the body, the latter being also provided with a transverse partition located at the enlargement and dividing the body into two compartments, said enlargement being adapted 105 to receive and form a seat for a screw plug arranged at right angles to the cylindrical body, a metal bushing embedded in it, a bolt extending longitudinally through the screw plug and having an inner end threaded in said bushing for securing the screw plug to the enlargement of the body to form a single unit, conductor bars embedded in the enlargement and projecting outwardly therefrom to form spaced blades for engaging interior contacts of the screw plug, shell contacts secured to the partition and electrically connected with each other and with one of the conductor bars and a central contact secured to the partition and electrically 110 connected with the other conductor bar.

In testimony whereof I have hereunto set my hand.
